(57) **CLAIM**

The ornamental design for an automobile wheel, as shown and described.

DESCRIPTION

FIG. 1—Top, front, left side perspective view of an automobile wheel;

FIG. 2—Front elevation view; and,

FIG. 3—Top plan view, the automobile wheel being rotationally symmetric.

The broken lines shown are included for the purpose of illustrating the unclaimed portions of the automobile wheel and form no part of the claim.
